STACKING CARRIERS

Milton C. Sherman, Coral Gables, Fla.

Original application September 15, 1950, Serial No. 185,059. Divided and this application August 25, 1952, Serial No. 306,093

3 Claims. (Cl. 220—97)

This invention relates to stacking carriers and more particular has for its primary object to provide article carriers which are stacked one upon another in a partly nested relationship and to provide for a flexibility between superposed carriers so as to protect articles therein from damage due to jarring or vibration during transportation. This application is a division of my application for Meter Carriers, filed September 15, 1950, Serial Number 185,059, and now abandoned.

A further object is to provide the upper portions of the side walls of each carrier with inset flexible marginal flanges which will engage within the side walls and engage in the raised bottom wall of the next carrier above it when a number of carriers are stacked, and to provide a cover which is received by the upper inset flexible marginal flanges of the upper carrier. Such flexible portions, while holding the next carrier above in position, are so formed as to yield to jolts both laterally and vertically while stacked carriers are in transit and yet not transmit severe shocks to the articles placed in the carriers.

Another object is to form such carriers of comparatively light sheet metal, such as aluminum, with the parts secured together so that there are no projecting elements on the outer sides of the carrier.

Further objects and advantages of my invention will appear in detail in the following description, taken in connection with the accompanying drawing, forming part of this specification, and illustrating a preferred form of carrier which has proven highly satisfactory in practice.

In the drawings:

Fig. 1 is a perspective view of a carrier in accordance with my invention.

Fig. 2 is a plan view thereof.

Fig. 3 is an enlarged vertical sectional view thereof taken substantially on line 3—3 of Fig. 2.

Fig. 4 is a detail perspective view of an upper corner of the carrier.

Fig. 5 is a fragmentary vertical sectional view taken through sides of a number of the carriers illustrating the cooperation of the carriers in stacking and further showing a cooperating cover member for the upper carrier of the stack.

Referring to the drawings, the carrier in accordance with my invention is rectangular in shape and includes a rectangular bottom wall 10 and four upright casing side walls 11 preferably of sheet metal. As shown the bottom wall 10 is provided with marginal downwardly extending flanges 12, which engage the casing side walls 11 a short distance above their lower edges and are secured at spaced points 13 as by riveting or preferably spot welding, for rigidly holding the bottom wall and side walls with respect to each other. Securing the bottom wall above the bottoms of the side walls provides a space at the bottom of the carrier, defined by the bottom wall and its flanges 12 and the lower marginal portions of the side walls, which constitute depending peripheral flanges below the bottom wall, into which inwardly offset upper marginal flanges 14 of another similar carrier may be re-

2

ceived. Thus any desired number of such carriers may be stacked one upon another as shown in Fig. 5. Likewise, as shown in Fig. 5, a cover 15 may be positioned over the flanges 14 of the upper carrier. Such a cover 5 renders the carrier or entire stack of carriers weather-proof.

As stated, the upright side walls 11 are formed of sheet metal, with the flange 14 along the upper edge of each side wall inset in a manner to preferably provide a 10 first or lower section 16 integral with its respective wall and flared inwardly and upwardly therefrom; a second or intermediate section 17 integral with section 16 and extending vertically therefrom; and a third or upper section 18, integral with section 17 and flaring upwardly and inwardly therefrom, as shown in Fig. 4. At each corner of the carrier, the ends of the flanges 14 are cut away to provide gaps 19, so that the flanges will be free of each other, separated by the gaps, and thus be afforded flexibility laterally and vertically, capable of absorbing 20 shocks or jarring when stacked carrier with a large number of articles therein, such as electric meters not shown in the drawings, are being transported. The arrangement, with the flaring sections of these flanges 14, provides a telescoping top edge which facilitates positioning of upper carriers thereon in stacking the carriers and when in position closely engages the interior surface of the bottom wall of the carrier stacked thereon as indicated in Fig. 5. These flanges 14 being flexible 25 absorb lateral shock due to their flexibility and the fact 30 that the bottom wall 10 of a carrier stacked thereon is entirely supported by the upper edge of these flanges 14, vertical jarring of the stacked carrier will also be absorbed.

The side walls of the container are in the example shown, formed from a blank of sheet metal with cut outs 35 defining the gaps 19 at the corners. The blank is bent to the rectangular formation shown and one end thereof is provided with a vertical flange extension 20 bent at right angles so as to engage the interior of the side portion at the other end of the blank, along its marginal edge, 40 to which the extension 20 is secured, preferably by spot welds 21, after which the bottom wall 10 is secured in place as above set forth.

The flanges 14 are each of a height in excess of the height of the depending peripheral flange below the bottom wall 10, of the carrier as shown in Figs. 3 and 5, so as to be received within the depending peripheral flange of another carrier stacked thereon and with its upper edge in supporting engagement with the under face of the bottom wall of the superjacent carrier. Thus 45 a principal object of the invention is carried out, that is, to provide for a flexibility between superposed carriers, the upper of which, in effect "rides" upon the upper marginal portions of the flanges 14, of the subjacent carrier, and not upon the bottoms of the flanges 14.

It will be seen that in this construction the major side wall portions 11 define the outer peripheral surface of the containers beyond which there are no projections even when several of the carriers are stacked and the cover 15 is positioned on the upper inset marginal flanges 50 14 thereof.

In use of such carriers, the arrangement of the bent inset upper flanges 14 has the further advantage in that in stacking of carriers, when a carrier is positioned over another, it is guided into position by the upper portions 18 thereof. In rough handling of the carriers a flange 14 55 may be bent outwardly but in view of its shape it will be received in the bottom of a superjacent carrier, or the cover 15, positioned over it and will be forced back into its normal proper position. With the ends of adjacent flanges 14 separated by the gap 19 such is sufficient to 60 provide the slight movement of the flanges with respect to each other without having adjacent upper corners

coming into engagement during any normal flexing movements of these flanges.

I claim:

1. A rectangular stacking carrier including four vertical side walls, and a bottom wall secured to said side walls at an elevation above the bottom edges of the latter providing a depending peripheral flange below said bottom wall, the upper edge of each of said four side walls provided with a flexible flange inwardly and upwardly offset with respect to the outer surface of its respective side wall, and each of said flanges separated at its ends from the flanges of the adjacent side walls to provide gaps between the flanges at the corners of the carrier, said flanges of the side walls providing means for stacking several carriers one above the other, with the bottoms of superposed carriers resting upon said flanges and allowing flexing of said flanges of the side walls to absorb shock between stacked carriers.

2. A stacking carrier as specified in claim 1 in which

said flanges at the upper edges of the side walls are each of a height greater than the distance between said bottom wall and the lower edges of said side walls.

5 3. A stacking carrier as specified in claim 2 in which each of said flanges of each of said side walls comprises a first section integral with its respective side wall flared inwardly and upwardly therefrom, a second section integral with said first section and extending vertically therefrom, and a third section integral with said second section and flared inwardly and upwardly with respect thereto.
